UNITED STATES PATENT OFFICE.

CLARENCE E. LOMAX, OF CHICAGO, ILLINOIS, ASSIGNOR, BY MESNE ASSIGNMENTS, TO
AUTOMATIC ELECTRIC INC., OF CHICAGO, ILLINOIS, A CORPORATION OF DELAWARE.

TELEPHONE SYSTEM.

Application filed January 2, 1925. Serial No. 61.

The present invention relates in general to telephone systems, but is particularly concerned with telephone equipment for use in private automatic exchanges which are 5 equipped with trunking facilities permitting connections to be extended between it and a main automatic exchange.

One feature of the invention provides conference call service between the private automatic exchange subscribers and a main automatic exchange subscriber on calls from the main automatic exchange.

Another feature lies in the provision of special night service, which is given after 15 the attendant at the private automatic exchange leaves her position.

Another feature has to do with an improved impulse repeating circuit shown in a selector repeater.

20 The cord circuit shown also contains novel supervisory circuits, which will be brought out in the description and claims.

The foregoing features are attained by the circuits diagrammatically illustrated in the 25 accompanying drawings which, when laid out with Fig. 3 at the left of Fig. 2 and with Fig. 1 above Figs. 3 and 2 with the corresponding lines in alignment, show sufficient of a telephone system to enable the invention 30 to be understood when the description is carefully followed.

Fig. 1 shows a calling substation of the 35 type ordinarily used by subscribers of automatic telephone systems, a line switch C of the well known continuous rotary type, and a selector repeater D of the well known vertical and rotary type.

Fig. 2 illustrates a trunk circuit T for establishing calls between the private automatic exchange and the main automatic exchange. This figure also shows a key K' used when night service is given, and a key K and jacks J'-J¹⁰ used for conference service.

45 Fig. 3 shows a cord circuit O, which is one of a number of similar cord circuits used by the attendant at the private automatic exchange for completing calls from the main exchange to subscribers of the private automatic exchange, for setting up conference connections, and, in certain cases, for establishing connections between private automatic exchange subscribers, and from private automatic exchange to main automatic exchange subscribers.

Fig. 4 shows a pair of relays used in addition to those shown in Fig. 2 under conditions which will be explained later.

It is believed that all features of the invention can be most clearly explained by describing the various operations which take place during the process of setting up connections. This has been done, the separate classes of connections being identified by appropriate headings.

In order to simplify the descriptions which follow, the abbreviation "P. A. X." is used for the words "private automatic exchange", and the abbreviation "M. A. X." is used for the words "main automatic 70 exchange".

Calls from the P. A. X. to the M. A. X.

When the receiver is removed at substation A a circuit is completed for the line 75 relay 13 of the line switch C. This circuit extends from grounded back contact and armature 20, line conductor 12, the switch-hook of substation A and its upper contact, through the receiver and transmitter, calling device springs S, line conductor 11, armature 19 and its resting contact, and the winding of relay 13 to battery. Relay 13, upon operating, at its armature 14 prepares a circuit for switching relay 16, and at 80 its armature 15 connects the test wiper 23 to the motor magnet 21 via armature 17 and its resting contact, and the interrupter springs of the motor magnet. The motor magnet now operates as long as the wiper 90 23 engages grounded or busy contacts. In the present case it is assumed that the trunk comprising conductors 28, 29 and 30 extending to the selector repeater D, is the first idle 95 trunk engaged by the wiper 23, at which time the formerly shunted switching relay 16 is energized in series with the motor magnet 21. Magnet 21 does not energize over this circuit due to the comparatively high resistance of relay 16. Relay 16, at 100 armatures 19 and 20, disconnects the line relay 13 and ground, and at the front contacts of these armatures extends the calling line to the line relay 31 of the selector repeater D, and at its armature 17 and its front contact prepares a holding circuit for 105 switching relay 16, which will be completed by relay 34 of switch D before the slow release relay 13 becomes deenergized. As soon as the calling line is extended to the con- 110

ductors 28 and 30, line relay 31 energizes, at its armature 32 prepares an impulsing circuit which will be described later, and at its armature 33 completes a circuit for slow 5 release relay 34. Relay 34 energizes, at its armature 36 opens a point in the release magnet circuit, and at the front contact of this armature prepares an operating circuit for the vertical magnet 47 and slow release relay 10 42, and at its armature 35 grounds conductor 29 in order to maintain the switching relay 16 energized after the release of relay 13. Everything is now in readiness for the 15 subscriber at substation A to dial the digit which is effective to position the wipers of the selector repeater D into engagement with an idle trunk extending to the M. A. X.

In the present case the bank contacts in the eighth level of the switch D are connected 20 with trunks extending to the M. A. X. The subscriber at substation A therefore operates his calling device in accordance with the digit 8, causing the line relay 31 to drop back a like number of times. Each time line relay 31 deenergizes a circuit is completed for the vertical magnet 47 and the slow release relay 42 in multiple. Relay 42 remains energized throughout the impulse series, while vertical magnet 47 operates in the usual 25 manner to move the wipers 55, 56 and 57 opposite the eighth level of bank contacts. As soon as the switch shaft is elevated one step, off normal springs 37 and 53 are closed. The closure of springs 37 is, however, without effect at this time, due to the energized 30 condition of slow release relay 34. The closure of off normal spring 53 completes a circuit for stepping relay 48. This circuit extends by way of grounded armature 35 and 35 its working contact, release trunk conductor 29, springs controlled by armature 45, armature 29, springs controlled by armature 45, armature 44 and its working contact, rotary off 40 normal springs 52, off normal springs 53, and the winding of stepping relay 48 to battery. Relay 48, upon operating, at its armature 45 and its working contact prepares an 45 operating circuit for the rotary magnet 51, and at its armature 49 completes a locking circuit for itself extending through interrupter 50 springs 59 and a shunt circuit about the winding of switching relay 58. Shortly following the termination of the transmission of the first series of impulses, relay 42 restores, and, in so doing, at its armature 44 55 completes a circuit for the rotary magnet 51 by way of grounded conductor 29, springs controlled by armature 45, armature 44 and its resting contact, working contact and armature 50, and the winding of magnet 51 to battery. Magnet 51 energizes 60 to rotate the wipers of the switch D one step and at its interrupter springs 59 opens the previously mentioned locking circuit for the stepping relay 48. This relay, accordingly, deenergizes, at its armature 49 breaks

its own locking circuit, and at its armature 50 breaks the initial energizing circuit of magnet 51. The further operation of the switch D now depends on the busy or idle condition of the trunk engaged by the test 70 wiper 56. If the first trunk is busy ground will be present on the test contact engaged by wiper 56, short circuiting the switching relay and preventing it from operating in series with the stepping magnet 48. Instead, the stepping relay 48 will be energized by ground supplied over wiper 56 via armature 45 and its resting contact and interrupter springs 59 to again complete an operating circuit for motor magnet 51. Magnet 51, accordingly, energizes to step the wipers into engagement with contacts associated with the next trunk. It will be seen from this that the stepping relay 48 and the rotary magnet 51 operate alternately as 75 long as the test wiper 56 engages busy test contacts. As soon as the wiper 56 comes into engagement with an ungrounded bank contact, which we will assume is contact 62, switching relay 58 will be no longer short 80 circuited and will therefore energize in series with the stepping relay 48. However, due to the high resistance of relay 58 the stepping relay 48 does not energize at this time. Relay 58, upon operating, at armature 46 disconnects the vertical magnet 47 to prevent its operation on subsequent impulse series, and at armature 45 removes the grounded conductor 29 from connection with armature 44, disconnects the wiper 56 from connection with the stepping relay 48 and instead connects this wiper directly to the grounded conductor 29. Relay 58 also 85 at its armature 54 completes a bridge across the outgoing end of the trunk. This circuit will be traced subsequently. The grounding of wiper 56 of the switch D makes the bank contact 62 and its multiples busy to all other switches having access to the same group of trunk lines. The grounding of bank contact 90 62 also causes a circuit to be completed over conductor 72, armature 95 and its resting contact, to the busy visual signal 128 at the attendant's position, and the trunk relay 88 in multiple to battery. The visual signal, 95 of course, informs the attendant that the trunk has been taken for use. Relay 88, upon operating, at its armature 101 disconnects the ring-down relay 94 and the polarized relay 86 from in bridge of the trunk 100 conductors 81 and 82, at armature 99 breaks a point in the locking circuit for the ring-down relay, and at armature 100 removes ground from conductor 87 so that relay 84 105 will not energize upon deenergization of the polarized relay 86, which deenergizes as a result of its circuit being opened at armature 101.

The bridge placed across trunk conductors 81 and 82 by the operation of armature 54 110

of switching relay 58 will now be traced. This bridge extends by way of trunk conductor 81, conductor 71, bank contact 61, wiper 55, front contact and armature 54, armature 32 and its front contact, impedance 39, wiper 57, bank contact 63, conductor 73, conductor 83, conductor 85, and the trunk conductor 82. The trunk conductors 81 and 82 terminate in a line switch identical to the 10 line switch C, and, therefore, immediately upon the closure of the bridge just described the line switch will immediately function to extend the trunk conductors into connection with a selector switch which may be of any 15 well known two-wire type.

The calling subscriber may now operate his calling device to transmit the first digit of the called subscriber's number. This time, at every deenergization of line relay 31 20 it opens, at its armature 32, the circuit for the line relay of the seized selector switch, causing that switch to advance its wipers into association with bank contacts in which conductors terminate extending to a desired 25 group of second selectors or connectors, depending on the size of the M. A. X. It will be noted that on each deenergization of line relay 31 a circuit is completed for slow release relay 42. This relay, therefore, 30 remains operated during the entire impulse series, and at its armature 43 connects the non-inductive resistance 67 in parallel with impedance 39. The non-inductive resistance 67 is provided to prevent the line relays of 35 the subsequently operated switches from momentarily deenergizing, which would result in the transmission of an extra impulse. This may occur when a direct short circuit is removed from around the impedance 39 40 upon deenergization of relay 42 due to the inductance of impedance 39. However, by placing a non-inductive resistance in multiple with the impedance sufficient current flow is permitted to maintain the impedance 45 partly saturated so that the current flow in the line relay circuit is not materially affected by the removal of resistance 67.

The further operations which take place when a connection is established with an 50 M. A. X. subscriber are old and well known, and, therefore, no attempt is being made to show or describe these operations or circuits. When conversation is completed release is brought about in the usual manner. The 55 line relay 31 of the switch D restores upon replacement of the receiver at station A on its switch-hook. Shortly following the release of relay 31 slow release relay 34 restores; at its armature 35 removes ground 60 from the holding circuit of line switch C, permitting this switch to restore to normal, and at armature 36 completes a circuit for the release magnet 38. Upon release of the switch D, ground is removed from conductor 72, and visual signal 128 at the attendant

operator's position as well as relay 88 of the trunk circuit restore to normal. The restoration of relay 88 again places the trunk circuit in condition for seizure.

Calls from P. A. X. subscribers to the attendant operator.

When a P. A. X. subscriber desires connection with the attendant operator, such connection is completed by the subscriber 75 dialling the digit 0, which results in the switch D selecting a trunk in the tenth level. Assuming the trunk comprising conductors 78, 79 and 80 to be idle when the wipers of the selector repeater D becomes associated 80 therewith, no ground will be present on the test contact 65 and the switching relay 58 of the selector repeater D will switch the connection through in the previously described manner. The relay 123 of the trunk 85 T and the repeating coils 124 and 125 are in bridge of conductors 78 and 80, which now extend to and through the substation A. Consequently relay 123 energizes and in turn causes the energization of slow 90 release relay 121. Relay 121, upon operating, at its armature 104 applies ground to test conductor 79. This ground is of no utility when selector repeaters are used, but is provided to feed ground back over conductor 95 79 in installations where ordinary selectors are used. Relay 121 also, at its armature 105, closes a bridge across conductors 147 and 148 for operating the call signal relay 151 at the attendant's position. This circuit extends by way of ground, upper winding of relay 151, armature 156 and its back contact, conductor 74, resting contact and spring 133 of key K', conductor 144, winding 126 of the repeating coil R, armature 105 100 105 and its working contact, winding 127 of the repeating coil, conductor 146, spring 137 and its resting contact, conductor 76, resting contact and armature 157, and the winding of relay 151 to battery. Relay 151 110 operates over this circuit and completes a circuit for the call signal lamp L².

The attendant upon noting the lighted condition of lamp L² will proceed to answer the call by inserting the plug P into the 115 answering jack J². This causes jack springs 158 to be closed, resulting in the energization of cut-off relay 154 and sleeve relay 167. Relay 154, upon operating, at its armatures 156 and 157 disconnects line relay 151 from 120 in bridge of conductors 74 and 76. Sleeve relay 167 in the cord operates to disconnect the tertiary winding of the attendant's head set and to complete the continuity of the tip conductor.

A circuit for supervisory relay 159 is now completed from ground, resistance 186, back contact and armature 172, lower winding of impedance coil 168, armature and back contact of relay 166, resting contact and spring 130

161 of key K², ring of plug P, ring terminal of jack J² to conductor 76, over the previously traced path to conductor 74, tip side of jack J², tip of plug P, spring 160 of key K² and its resting contact, winding of relay 159, armature of relay 167 and its working contact, upper winding of impedance 168, armature 171 and its resting contact, and resistance 185 to battery. The operation of relay 159 results in the operation of relay 162 which, at its armature 163, connects non-inductive resistance 157 in multiple with relay 159 to improve transmission and at armature 164 opens a point in the circuit of supervisory lamp L³.

Calls between P. A. X. subscribers via the attendant's position.

As hereinbefore pointed out, ordinarily, 20 the various P. A. X. subscribers will set up connections between themselves without the assistance of the attendant operator. However, if for any reason a P. A. X. subscriber desires to establish a connection to some 25 other P. A. X. subscriber via the attendant's position, he may do so by calling the attendant in the usual manner, and request the attendant to call the desired party. The call is answered, of course, by the attendant 30 placing the plug P of her cord into the jack, such as J², of the trunk over which the call was set up. We will assume that a P. A. X. subscriber has called the attendant, and that the subscriber at substation A is desired. 35 Accordingly, the attendant operator tests the condition of the desired line by touching the sleeve of jack J³ with the tip of a plug of a cord not in use to determine the busy or idle condition of substation A. If the 40 called line is busy the attendant will inform the subscriber. Assuming, however, that the station A is idle, the attendant inserts the plug P' into the jack J³. In order to eliminate the possibility of operating the 45 line relay of switch C, the tip conductor is normally held open at armature 18 of cut-off relay 16. This makes it necessary that the cut-off relay operates before the tip conductor can be cut through. The closure of 50 jack springs 184 causes ground to be applied to conductor 26, to energize the cut-off relay 16 of the line switch C. Since the terminal of sleeve relay 169 is connected with ground, and the sleeve contact of the plug P' is now 55 grounded by the sleeve of jack J³, this relay will not be operated. The attendant operator may now signal the desired subscriber by operating ringing key K⁴ momentarily. She may then operate her 60 listening key K³ to make certain that the called subscriber has responded. In this connection, talking battery is supplied to the subscriber at substation A by the battery and ground supplied through the back contact and armatures 171 and 172 of the sleeve 65

relay 169, and the upper and lower windings of the impedance coil 168 which are now in bridge of the called line. Disconnect supervision is provided by the lamp L³ which becomes lighted when the calling 70 subscriber replaces his receiver.

If the attendant operator desires, she may set up calls between the P. A. X. subscribers so that the supervision of the call is under control of the called subscriber. In such 75 case when a call comes in the attendant either originally answers the call by inserting the plug P in jack J² and then reverses the cord when she learns that another P. A. X. subscriber is desired, or answers 80 the call by inserting the plug P' into jack J². In either case when plug P' is inserted in jack J² relay 169 is not operated, due to ground supplied by springs 158. Since the 85 relay 167 is not operated the attendant may use the same cord to test the called line. When the called subscriber answers relays 159 and 162 energizes to extinguish supervisory lamp L³.

Calls extending from the P. A. X. to the M. A. X. via the attendant operator's position.

On certain occasions it may be desirable to have the attendant set up connections to subscribers of the M. A. X. We will assume that the subscriber at substation A sets up a connection, in the manner hereinbefore described, to the attendant operator's position, requesting the attendant operator to extend 95 the call to a M. A. X. party. The attendant operator, upon noting that the trunk T is idle, inserts the plug P' of her cord O in the jack J of the trunk T. Sleeve relay 169 in the cord O, visual signal 128, and relay 88 100 of the trunk T are operated over a circuit extending from ground, winding of relay 169, sleeve of plug P', sleeve side of jack J, conductor 89, and the visual signal 128 and relay 88 in multiple to battery. Relay 88, 105 upon operating, at its armature 101 removes the polarized relay 86 and the ring-down relay 94 from in bridge of the outgoing trunk conductors 81 and 82, at its armature 100 opens a point in the operating circuit of relay 84, and at armature 99 opens a point in the locking circuit of ring-down relay 94. The relay 169 in the cord operates, and at its armatures 171 and 172 completes a direct 110 current bridge across the tip and ring conductors of the cord. Since these conductors are in direct connection with conductors 81 and 82 of the trunk T, the line switch in which these conductors terminate at once 115 extends the connection to a selector of the M. A. X. Jack springs 81' of the jack J are also closed now, and, since the polarized relay 86 is now deenergized, a circuit is completed extending from ground, working contact and springs 81', conductor 87, resting 120

125

130

contact and armature 98, and the winding of relay 84 to battery. Relay 84 operates and at its armature 95 applies ground potential to conductor 72 in order to make the trunk T busy to the selector repeater D and other similar selector repeaters having access to trunk T. The attendant operator may now operate the key K³, thereby connecting her head-set and calling device S' into operative relation to the cord. The attendant operator is now ready to set the switches of the M. A. X. in accordance with the number of the desired subscriber. Upon forward movement of the calling device S' its off normal springs are closed, completing a circuit for the slow release relay 179 which, in turn, operates and at its armature 181 places a shunt about the attendant's receiver, and at its armature 180 completes a circuit via springs 176 of key K³ for the calling device control relay 170. Relay 170, upon operating, bridges the calling device across the tip and ring conductor of the cord in substitution for the bridge extending through the impedance coil 168. The process of transmitting impulses over the conductors 81 and 82 to the various switches in the M. A. X. is well known and, therefore, need not further be described. It is sufficient to point out that when the connection is established talking battery is supplied to the P. A. X. subscriber via the line relay of the connector of the M. A. X. This battery also serves to operate the supervisory relay 159 which, of course, remains energized as long as the calling subscriber has his receiver off the hook. However, the called subscriber may recall the attendant operator by operating his switchhook, which results in battery in the trunk being reversed each time the back bridge relay in the connector deenergizes. This causes supervisory relays 159 and 162 to momentarily restore causing lamp L' to be flashed. When the conversation is completed disconnect supervision is also provided by the lamp L'. The calling subscriber, upon replacing his receiver, causes the disconnection and release of the various switches set up in the P. A. X., while the removal of the plug P' from the trunk circuit T causes the switches in the M. A. X. to be restored to normal.

Calls from M. A. X. to P. A. X.

Since the attendant handles all calls extended to the P. A. X., any M. A. X. subscriber desiring connection with a P. A. X. subscriber sets up the connection in well known manner over a connector in the M. A. X. which seizes an idle trunk line extending to the P. A. X. The seizure of this trunk and the act performed by the connector in transmitting ringing current thereover is accomplished in the same manner, so far as the calling subscriber is concerned, as when said subscriber extends a connection to some subscriber of the M. A. X. It is believed sufficient to say that when the trunk conductors 81 and 82 are seized the cut-off relay of the line switch associated therewith is operated to disconnect the normal battery and ground connections therefrom. This causes the deenergization of polarized relay 86 in the trunk circuit T which, upon restoring its armature 98, completes a circuit for the slow release relay 84. Relay 84, upon operating, at its armature 95 disconnects the conductor 72 from connection with the visual signal 128 and relay 88 and connects it to ground, thereby making the trunk T busy to all selector repeaters, such as D, at test contact 62 and all multiples thereof. The transmission of ringing current over conductors 81 and 82 causes ring-down relay 94 to operate, the circuit extending from conductor 81, back contact and armature 101, upper winding of ring-down relay 94, condenser 139, spring 135 of key K' and its resting contact, conductor 83, conductor 85 and trunk conductor 82. Relay 94, upon operating, at its armature 103 completes a locking circuit for itself, and at armature 102 completes a circuit for the visual signal L to notify the attendant that a call is awaiting her attention.

The attendant operator, upon noting the lighted condition of lamp L, answers the call by inserting plug P' into jack J. The insertion of plug P' into jack J, resulting in the closure of jack springs 81', causes ground to be applied to conductor 87 independent of armature 100 of relay 88. At the same time a circuit is completed for sleeve relay 169 of the cord circuit O and relay 88 in series. This circuit extends from ground, winding of relay 169, sleeve contact of plug P', sleeve of the jack J, and the winding of relay 88 to battery. Relay 169, upon operating, at its armatures 171 and 172 removes battery and ground from the tip and ring conductors of the cord and at the front contact of these armatures completes a direct current bridge across these conductors to cause the energization of the ring cut-off relay in the connector, which results in the talking connection being extended to the cord O.

Relay 88, upon operating, at its armature 101 disconnects polarized relay 86 from in bridge of the trunk, at this same armature opens the initial operating circuit of ring-down relay 94, and at armature 99 opens the locking circuit of this relay. As a result, ring-down relay 94 deenergizes, causing the call signal lamp L to be extinguished.

The attendant now operates her listening key K³ to connect her head set with the cord O so that she may converse with the calling subscriber to ascertain the name or local number of the desired P. A. X. subscriber,

It will be assumed, in the present case, that the subscriber at substation A is desired. The attendant will, accordingly, insert the plug P of her cord in the jack J^3 . The cut-off relay 16 is operated by the closure of springs 184 of the jack J^3 when the plug P is inserted therein. The attendant now proceeds to signal the called station by operating ringing key K^2 . When the called subscriber responds following the restoration of key K^2 a circuit for supervisory relay 159 is completed in series with the calling station and battery and ground supplied by the back bridge relay of the connector in the M. A. X. Relay 159, upon operating, completes a circuit for relay 162, which also operates. Relay 162 at armature 163 opens the normal A. C. bridge extending across the tip and ring conductors of the cord, at the front contact of this armature connects a non-inductive resistance in multiple with relay 159 to improve transmission, and at armature 164 opens a point in the operating circuit of supervisory lamp L^2 in order to prevent its being lighted at this time.

When the conversation between the two subscribers has been completed, the replacement of the receiver at the calling station brings about the release of the various switches in the M. A. X. Since the called party, who in the present case is the P. A. X. subscriber, is still on the line, battery and ground for maintaining the supervisory relay 159 operated, which was supplied by the back bridge relay of the connector in the M. A. X., prior to release, is now provided by battery and ground connections of the line relay of a selector switch, which is seized by the line switch in which the trunk normally terminates.

When the called subscriber replaces his receiver, the circuit for supervisory relay 159 is opened. Relay 159, upon restoring, opens the circuit of relay 162 which, upon restoring, completes a circuit for the supervisory lamp L^2 to notify the attendant that disconnection is desired. The withdrawal of the plug P from the jack J^3 causes the restoration of the cut-off relay 16 and restoration of relay 167. The withdrawal of the plug P' from the associated jack results in the restoration of the armature of relay 169 in the cord circuit, and in the deenergization of the visual signal 128, and relay 88 in the trunk circuit. The relay 88, upon restoring, again connects the ring-down relay 94 and the polarized relay 86 in bridge of the trunk. Relay 86 immediately operates, assuming that the M. A. X. connector has restored, and at its armature 98 opens the circuit of slow release relay 84. This relay, accordingly, restores to remove the busy condition from conductor 72 extending to the multiple test contact accessible to the selector repeater D and other similar selectors. The trunk T is

now available for use for extending connections in either direction.

Calls from M. A. X. toll operators to P. A. X.

70

Had the connection described in the foregoing been established by a toll operator in the M. A. X. the transmission of ringing current to the trunk conductors 81 and 82 would have been brought about by the toll 75 operator operating her usual ringing key. Otherwise, the operation would have been the same except that, since the toll operator has facilities for applying ringing current to the trunk at will, the cord circuits at the 80 P. A. X. are so arranged that, should the toll operator desire to recall the attendant after the P. A. X. subscriber has replaced his receiver, but before the attendant has pulled down the cord, she may do so by 85 operating her ringing key. This will cause the alternating current relay 165 in the attendant's cord to operate to complete a circuit for slow release relay 166. Relay 166, upon operating, at its lower armature opens 90 a point in the ring conductor of the cord to prevent the ringing current passing to the signalling device of the P. A. X. subscriber, and at its upper armature completes a circuit for supervisory signal L^1 . 95 The lighted condition of this signal notifies the attendant operator that the toll operator desires to communicate with her. The attendant operator, accordingly, operates her listening key K^2 and converses with the toll 100 operator.

Conference service.

It will now be assumed that, in the connection between the P. A. X. and M. A. X. 105 subscribers, it is desired to extend the call to one or more other P. A. X. subscribers. Under these circumstances the P. A. X. subscriber simply actuates his switchbook causing the supervisory lamp L^2 to be flashed 110 as a result of the periodic deenergization and energization of relays 159 and 162. The attendant operator upon noting the flashing of lamp L^2 immediately operates her listening key K^2 . The attendant, after notifying the subscribers of her presence, will be informed of the other subscriber or subscribers desired in on the connection, and after receiving this information will restore her listening key to normal. The attendant 115 now sets up connections to other P. A. X. subscribers in the same manner that connection was made with the subscriber at substation A by inserting the plugs of other cords corresponding to plug P' of the cord circuit 120 O in the jacks J^1 — J^{10} , or other similar jacks in multiple therewith, not shown. The conference key K of the trunk T will now be operated by the attendant to connect the 125 trunk T to the conference jacks. It should be 130

noted at this point that these jacks are preferably individual to an attendant's position but common to a plurality of trunk lines. The same is true of course of the two supervisory relays 92 and 93 and the condenser 140 as is apparent from the drawing, Fig. 2. The points where other trunk lines, not shown, are connected have been denoted by arrows branching off from the conductors 10 which connect the conference jacks J^1 — J^{10} and the relays 92 and 93 to the key K.

The operation of key K in addition to connecting the conference jacks in bridge of the trunk conductors 81 and 82, at its 15 springs 129 and 131 and their working contacts, at spring 130 and its working contact connects ground to conductor 72 extending to the multiplied test contacts terminating in the banks of the selector repeater, such as 20 D, and prepares a substitute holding circuit for relay 88 and busy visual signal 128 which becomes effective in case the originally established connection is broken while the conference is being carried on with other subscribers, as will be made clear subsequently. Key K also, at its spring 132 connects supervisory control relay 93 to grounded conductor 89. This relay, accordingly, operates to close a point in the circuit of lamp L' .

It will be noted that the branch conductor connecting the ring conductor of the trunk T to the ring terminal of the conference jacks includes a supervisory relay 92. This relay is, accordingly, energized to prevent 35 the lighting of lamp L' so long as any P. A. X. subscriber is connected in on the conference. However, when the P. A. X. subscribers in the conference all have replaced their receivers relay 92 restores, causing 40 supervisory lamp L' to become lighted to inform the attendant operator that the conference has been terminated and that the conference key K should be restored. The restoration of this key effects the disconnection of the conference jacks from association with this particular trunk, rendering them available for use in connection with any other trunk, removes ground from conductor 72 to render the trunk available to 45 P. A. X. subscribers for outgoing calls, to cause the restoration of the busy visual signal 128, and the relay 88. Relay 88, upon restoring, reconnects the ring-down relay 94 and polarized relay 86 in bridge of conductors 81 and 82 of the trunk T.

It may often occur that the originally called P. A. X. subscriber, after securing a number of other P. A. X. subscribers in on a conference, is no longer needed in on the connection. Under these circumstances such subscriber will replace his receiver, thereby informing the attendant, in the hereinbefore described manner, that a disconnection is desired. The attendant will, accordingly, 55 disconnect the cord O from jack J^3 , and jack

J, respectively. The removal of plug P' from the jack J results in ground being removed from conductor 87 and the sleeve of jack J. As a result, relays 88 and 84 restore. Relay 88, upon restoring, at its armature 70 101 again connects relay 86 in bridge of the trunk. The battery flow from the back bridge of the connector is in the opposite direction to that normally supplied by the outgoing line switch, and, therefore, the relay 86 remains deenergized. However, since at this time the conference key K is thrown, the closure of armature 100 and its back contact is ineffective to again energize relay 84. A substitute circuit for relay 88 75 80 and the visual signal 128 is now provided which extends by way of grounded spring 130 of key K and its working contact, conductor 72, armature 95 and its back contact, and the windings of relays 88, 93 and visual 85 signal 128 in multiple to battery. Relay 88 operates without effect at this time, other than to disconnect the polar relay 86 from in bridge of the trunk.

Night service.

Connections from the P. A. X. to main exchange are extended automatically. Night service calls in this direction are handled as are the day service calls.

When the attendant leaves her position, however, she operates the night service keys K' associated with the trunk T as well as all other similar keys associated with the other trunks extending between the P. A. X. 95 100 and M. A. X.

The key K', when in its operated position, at its spring 134 and its working contact supplies ground to conductor 91, thereby preparing a circuit for the direct current signals 142 and 143; at springs 133 and 137 disconnects conductors 144 and 146 from their normal connection with conductors 74 and 76, and connects these former conductors with trunk conductors 81, 82, and at spring 110 136 connects conductor 145 with armature 96 of the relay 84 and its grounded resting contact. It will be appreciated from this that when the night service key is operated the facilities for calling the attendant are 115 cut out of service and the trunks normally accessible to trunks extending to the attendant's position are made busy by ground supplied by the resting contact and armature 96 of relay 84, being fed back through working contact and spring 136 of the key K' to the test conductor 79. It follows that if any subscriber attempts to call the attendant the selector repeater will rotate its wipers off the bank and give the usual all trunk 120 busy signal to the subscriber. Key K' also at its spring 135 opens the circuit for ring-down relay 94 so that it cannot be operated by ringing current transmitted to the trunk conductors 81 and 82. However, alternating 125 130

current relay 122, which is in series with windings 126 and 127 of the repeating coil R, is now in bridge of the conductors 81 and 82 and responds to any ringing current transmitted thereover. Each time relay 122 is actuated it completes a circuit for the common signals 142, 143, at its armature 106, so that any subscriber in the P. A. X. upon hearing the operation of any one of these signals is informed that a P. A. X. subscriber is desired. Relay 86 also restores due to the reverse direction of current supplied by the connector, and, in so doing, completes a circuit for relay 84, the circuit extending from grounded spring 130 of key K and its resting contact, resting contact and armature 100, resting contact and armature 98, and the winding of relay 84 to battery. This relay, upon operating, at its armature 95 supplies ground potential to test conductor 72 to make the trunk busy to P. A. X. subscribers attempting to make outgoing calls, and at its armature 96 removes the normal busy condition from the test conductor 79 so that this trunk may be seized by a selector repeater answering the call.

It will be assumed that the subscriber at substation A hears the signals 142 or 143 being operated and decides to answer the call. To do this the subscriber merely dials the digit 0 which causes the selector repeater to position its wipers opposite the tenth level of bank contacts and to test then for the trunk seized which is identified from the idle trunks by the ground having been removed from its test contact. As soon as the wipers of the selector repeater engage the spring contacts 64, 65 and 66 the selector repeater switches through in the usual manner, and in so doing renders this trunk busy to other similar switches. Since the selector repeater places a direct current bridge across conductors 78 and 80, relay 123 in the trunk circuit is energized. This relay upon operating completes a circuit for relay 121 which, at its armature 105, places a direct current shunt about A. C. relay 122 which causes the ring cut-off relay in the connector of the M. A. X. to energize to cut off the ringing current and to switch the connector into talking position. Conversation may now be carried on through the repeating coil R.

It will be noted that although the ring cut-off relay of the connector removes ringing current from the trunk conductors 81, 82, since the signaling devices 142, 143 are common to all incoming trunks, these signals continue to operate as long as there is a call on any trunk awaiting the attention of a P. A. X. subscriber.

When the conversation is completed the calling subscriber, in replacing his receiver, causes the switches in the M. A. X. to be restored in the usual and well known manner,

while the replacement of the receiver at the substation A causes the line switch C, selector repeater D, and the various operated relays in the trunk T to be restored to normal in substantially the same manner as described when a connection was set up to the attendant operator. Of course, since the key K' is in operated position the deenergization of relay 84 again renders the conductors 78, 79 and 80 busy to the selector repeater D until a trunk is again taken for use by an M. A. X. subscriber.

If the P. A. X. subscriber who answered the call is other than the desired party, the P. A. X. subscriber may request the M. A. X. subscriber to hold the wire until the desired subscriber answers. The P. A. X. subscriber then replaces his receiver, causing the line and release relays 123 and 121 to restore. The P. A. X. subscriber now gets in touch with the desired subscriber who will proceed to connect with the trunked line in the same manner as did the subscriber at substation A; the trunk having been rendered accessible to a selector repeater, such as D, upon the release of the selector D.

Night service as modified by the addition of relays shown in Fig. 4.

In certain installations, it may prove more desirable to require a desired subscriber to use the subscriber's telephone who answers the incoming night call. For it will be appreciated that in the arrangement just described, should the incoming traffic be rather heavy, there is a possible chance that a desired P. A. X. subscriber, in attempting to set up a connection with a trunk call answered by some other subscriber, may obtain, instead, connection with a trunk which has not previously been answered.

By connecting the relays of Fig. 4 into association with the trunk T by attaching terminals 107 to 110', inclusive, to terminals 107 to 110, respectively, the operation will be so changed that when the original answering P. A. X. subscriber replaces the receiver at substation A, the trunk T will be maintained busy to all P. A. X. subscribers until the M. A. X. subscriber restores his receiver, making it necessary for the desired P. A. X. subscriber to use the telephone of the subscriber answering the call. The operation is as follows: When the subscriber at substation A replaces his receiver, causing the release of line relay 123 of the trunk T, an impulse is transmitted from the grounded armature of relay 123 and its resting contact, armature 106 and its working contact, terminals 108 and 108', and the winding of relay 115 to battery. This relay operates and a moment later, upon restoration of relay 121, a circuit is completed for slow relay 112 from grounded armature and back contact of relay 123, armature 106 and its back

contact, terminals 109 and 109', respectively, armature of relay 115 and its working contact, and the winding of relay 112 to battery. Relay 112, upon operating, at its 5 armature 113 completes a locking circuit for itself in multiple with relay 84, and at its armature 114 applies ground to test conductor 79 to prevent the seizure of the trunk by a P. A. X. subscriber prior to its release by 10 the M. A. X. subscriber. This method of operation also guards against possible trouble which might result if the first trunk of the group is held in use for an unusual period by some M. A. X. subscriber. 15 Finally, when the connection is released by the M. A. X. subscriber, resulting in the normal battery and ground potential supplied by the line switch being again applied to conductors 81 and 82, relay 86 again energizes, thereby causing the restoration of slow 20 release relays 84 and 112. Relay 84, upon restoring, at its armature 96 again places ground on the private conductor 79 to replace that formerly supplied by armature 25 114 of slow release relay 112.

In certain installations where the P. A. X. is a very short distance from the M. A. X. it may prove more economical to utilize ordinary first selectors in substitution for selector repeaters such as D. This may be done without necessitating any changes in the trunk circuit T, either with or without the modification shown in Fig. 4. In the use of a selector when the trunk T is seized, 30 relay 121 at its armature 104 applies ground to conductor 79 to maintain the selector and line switch in operated position.

When the trunk circuit is used as modified by the addition of Fig. 4, it is essential that, 40 in order to permit a P. A. X. subscriber to release from the trunk independent of the M. A. X. subscriber, ground potential for maintaining the selector and line switch of the calling line be removed. This is taken care of by relays 112 and 121. It will be noted that there is a short interval 45 between the deenergization of relay 121 and the energization of relay 112, (relay 112 being slow to pull up) during which no ground potential is present on test conductor 79. This interval is very short but is sufficient to allow the selector to respond so that it and the line switch of the calling line will restore.

Having described a system in which are 50 incorporated the various features, which are considered new and on which Letters Patent is desired, these features will now be pointed out in the appended claims.

What is claimed is:

1. In a telephone system, private and main automatic exchanges, trunk lines interconnecting said exchanges, an attendant operator's switchboard equipped with facilities for manually answering and extending

connections from said trunk lines to subscribers of the private automatic exchange, a set of call signals common to said trunks, manually operable night service keys, there being one such key for each trunk, means 70 rendered effective jointly by the operation of a key and the seizure of a corresponding trunk for rendering the same accessible to any substation of the private automatic exchange, and means rendered effective by a 75 flow of signalling current transmitted from the main exchange for causing the operation of said call signals.

2. In a telephone system, main and private automatic exchanges, trunk lines interconnecting said exchanges, an automatic switch having direct access to said trunk lines via two paths, means for making said trunk lines busy, means for rendering said trunk lines inaccessible via one of said paths when 80 the trunks are idle, and means for rendering said trunks inaccessible to said automatic switch via the other path when said trunk lines are in use.

3. In a telephone system, main and private 90 automatic exchanges, trunk lines interconnecting said exchanges, an automatic switch having direct access to said trunk lines over a plurality paths, and means for preventing said automatic switch from seizing one 95 of said trunks over a particular path unless the trunk has already been taken for use.

4. In a telephone system, main and private automatic exchanges, trunk lines interconnecting said exchanges, an attendant operator's switchboard at the private automatic exchange equipped with facilities for manually extending connections to subscribers of the private automatic exchange, a plurality of conference jacks individual to the attendant's position but common to said trunk lines, means at the attendant operator's position for setting up connections to a plurality of subscribers of the private automatic exchange and for connecting said subscribers' 100 lines with said jacks, and means associated with the inter-exchange trunk in use for simultaneously connecting said private automatic exchange subscribers' lines in talking relation with said trunk line.

5. In a telephone system, an automatic switch, other automatic switches accessible thereto, means for transmitting impulses to said first automatic switch to cause the same to select another automatic switch, an impulse repeating device in said first automatic switch including an impedance element, and means for including a non-inductive resistance in multiple with said impedance only during the transmission of impulses to said second automatic switch to prevent an extra impulse being transmitted by the pulsing relay thereof at the end of an impulse series.

6. In a telephone system, an established 124

connection between a private automatic exchange subscriber station and a toll operator including a cord circuit, a signalling device at said subscriber's station, means in said cord effective upon the replacement of the receiver by the private automatic exchange subscriber for signalling an attendant operator at the private automatic exchange, a second signal in said cord, and means placed under control of the toll operator for operating said second signal to call the attendant, said last means also effective to prevent the signalling device of the private automatic exchange subscriber being operated by the toll operator.

7. In a telephone system, an established connection between a private automatic exchange subscriber and a subscriber of a main automatic exchange including a cord at an attendant operator's position in the private automatic exchange, a supervisory signal provided for the subscriber in the private automatic exchange for giving an attendant operator disconnect supervision, and means controlled by the subscriber in the main automatic exchange for causing said supervisory signal to be flashed when an attendant operator is desired in on the connection.

8. In an impulse repeater, an impulse repeating relay, an impulse repeating circuit including contacts of said relay, an inductive resistance normally included in said circuit, a non-inductive resistance, a second relay having contacts for connecting said non-inductive resistance in multiple with said inductive resistance, and means controlled by said first relay for causing the operation of said second relay while impulses are being repeated.

9. In an impulse repeater, an impulse repeating circuit including an inductive impedance element, a non-inductive resistance, and means for including said non-inductive resistance in multiple with said impedance only while impulses are being repeated.

10. In a telephone system, an inter-office trunk connecting a first with a second automatic exchange and terminating at the first exchange at an operator's position, subscribers' lines in said first exchange, a common signal device for said lines, a relay and a condenser bridged across said trunk, said relay being responsive to a flow of signalling current applied to said trunk at said second exchange to operate a signal at said operator's position, a manually operable switching device associated with said trunk, and means for simultaneously signalling said subscribers' lines at said first exchange by operating said common signal device when said switching device is operated and signalling current applied to said trunk at said second exchange.

11. In a telephone system, private and main automatic exchanges, trunk lines inter-

connecting said exchanges, an attendant operator's position at said private exchange, a set of call signals common to said trunks and to all subscribers of said private exchange, a manually operable switching device associated with each trunk, and means rendered effective jointly by the operation of said switching device and by a flow of signalling current transmitted from the main exchange over a trunk line for operating said call signals.

12. In a telephone system, main and private automatic exchanges, trunk lines interconnecting said exchanges, an automatic switch having terminals arranged in horizontal levels, said switch having access to said trunk lines via two levels, means for making said trunk lines busy, means for rendering said trunk lines inaccessible via one of said levels when the trunks are idle, and means for rendering said trunks inaccessible to said automatic switch via the other level when said trunk lines are in use.

13. In a telephone system, main and private automatic exchanges, trunk lines interconnecting said exchanges, an automatic switch having terminals arranged in horizontal levels, each of said trunk lines connected to two of said levels, subscriber controlled means for operating said automatic switch to seize one of said trunk lines over a certain level to extend a call, and means for preventing said automatic switch from seizing one of said trunk lines over the other level unless the trunk has already been taken for use.

14. In a telephone system, a first and a second automatic exchange, trunk lines interconnecting said exchanges, an automatic switch at said first exchange having terminals arranged in horizontal levels, each of said trunk lines connected to two of said levels, subscriber controlled means for operating said automatic switch to seize one of said trunk lines over a certain level to extend a call from said first to said second exchange, and means for preventing said automatic switch from seizing one of said trunk lines over the other level unless the trunk has already been taken for use by a subscriber extending a call from said second to said first exchange.

15. In a telephone system, a first and a second automatic exchange, trunk lines interconnecting said exchanges, an automatic switch at said first exchange having direct access to said trunk lines over a plurality of paths, means controlled by a calling subscriber for operating said automatic switch to seize one of said trunk lines over a certain path to extend a call from said first to said second exchange, and means for preventing said automatic switch from seizing one of said trunk lines over another path unless the trunk has already been taken for use.

use by a party extending a call from said second to said first exchange.

16. In a telephone system, main and private automatic exchanges, an automatic switch having terminals arranged in groups in horizontal levels, trunk lines interconnecting said exchanges, each of said trunk lines accessible to said switch over a plurality of levels, and means for normally preventing the seizure of any of said trunk lines over a certain level while permitting the seizure over another level.

17. In a telephone system, a first and a second automatic exchange, trunk lines interconnecting said exchanges, an automatic switch having direct access to said trunk lines over a plurality of paths, and means in said first exchange for permitting the seizure of one of said trunk lines over a certain of said paths only if said trunk line has already been taken for use in the extension of a call from said second to said first exchange.

18. In a telephone system, main and private automatic exchanges, an automatic switch having terminals arranged in groups in horizontal levels, trunk lines interconnecting said exchanges, each of said trunk lines connected to a plurality of said levels, and means for preventing said automatic switch from establishing connection with one of said trunk lines over a particular level unless the trunk has already been taken for use.

19. In a telephone system, main and private automatic exchanges, trunk lines interconnecting said exchanges, an attendant operator's switch-board at the private automatic exchange equipped with facilities for manually extending connections to subscribers of the private automatic exchange, a plurality of conference jacks and supervisory relays individual to the attendant's position but common to said trunk line, means at the attendant operator's position for setting up connections to a plurality of subscribers of the private automatic exchange and for connecting said subscribers' lines with said jacks, means associated with the inter-exchange trunk in use for simultaneously connecting said private automatic exchange subscribers' lines in talking relation with said trunk line, and means operated by said supervisory relays upon the last private automatic exchange subscriber withdrawing from the connection for signalling said attendant.

20. In a telephone system, a first and a second automatic exchange, trunk lines interconnecting said exchanges, manually controlled means at said first automatic exchange including a plurality of conference jacks for connecting a plurality of subscribers' lines to a trunk, means associated with said trunk for simultaneously connecting said subscribers' lines in talking relation with said trunk line, supervisory means

common to said trunk lines and associated with said conference jacks, and means operated by said supervisory means upon the last subscriber connected to said conference jacks withdrawing from the connection for signalling the attendant.

21. In a telephone system, first and second automatic exchanges, trunk lines interconnecting said exchanges, said trunk lines terminating at said first automatic exchange in individual jacks at an attendant operator's switchboard, a plurality of auxiliary jacks common to said trunk lines for connecting a plurality of subscribers' lines to a trunk, means associated with said trunks for simultaneously connecting said subscribers' lines in talking relation with said trunk lines, supervisory relays common to said trunk lines and associated with said conference jacks, and means operated by said supervisory relays when the last subscriber withdraws from the connection set up over said conference jacks for signalling the attendant.

22. In a telephone system, an automatic switch, other automatic switches accessible thereto, means for transmitting impulses to said first automatic switch to cause the same to select another automatic switch, an impulse repeating device in said first automatic switch including an impedance element and a non-inductive resistance, said resistance normally out of circuit, and means for including said non-inductive resistance in parallel to said impedance only during the transmission of impulses to succeeding switches.

23. In a telephone system, an automatic switch having access to other automatic switches, means for transmitting impulses to said first automatic switch to establish connection with succeeding automatic switches, an impulse repeating device in said first automatic switch including an impedance element and a non-inductive resistance, and means for including said non-inductive resistance in parallel to said impedance only during the transmission of impulses to succeeding switches.

24. In a telephone system, a private automatic exchange, subscribers' stations therat each having a signalling device, a main exchange, an attendant operator's position at said private exchange, a toll operator's position at said main exchange, an established connection between a private automatic exchange subscriber and said toll operator including a cord circuit, means in said cord circuit effective upon the replacement of the receiver by the private automatic exchange subscriber for signalling said attendant operator at the private automatic exchange, a second signal in said cord circuit, means operable by ringing current applied by said toll operator to the talking conductors of

said cord to recall the attendant, and means for preventing the operation of the signalling device of the connected private automatic exchange subscriber's substation during the time ringing current is applied by the toll operator.

25. In an automatic telephone system, a first and a second exchange, subscribers' lines in said first exchange, an attendant operator's position in said first exchange, a toll operator's position in said second exchange, an established connection between a subscriber at said first exchange and said toll operator at said second exchange including a cord circuit, means in said cord circuit operable upon said subscriber withdrawing from said connection for signalling said attendant operator at said first exchange and for closing an A. C. bridge across the line conductors leading to said second exchange, a second signal in said cord circuit operable by ringing current applied by said toll operator to the talking conductors of said cord to recall said attendant, and means for preventing the transmission of ringing current to the subscriber's substation.

26. In a telephone system, main and private automatic exchanges, trunk lines interconnecting said exchanges, an attendant operator's position at the private automatic exchange, a subscriber controlled automatic switch having access to said trunk lines and

to said operator's position over two distinct paths, means at said operator's position for receiving calls from the main exchange and for extending them manually to subscribers of the private automatic exchange, a manually operable night service key at said operator's position, and means actuated by said key to permit subscribers of said private automatic exchange to establish connection with a calling main exchange subscriber by means of said automatic switch and over said path normally provided for calling the attendant operator's position.

27. In a telephone system, an established connection between a private automatic exchange subscriber and a subscriber of a main automatic exchange including a cord at an attendant operator's position in the private automatic exchange, and supervisory means in said cord jointly controlled by the private and by the main automatic exchange subscriber for giving disconnect supervision upon the private automatic exchange subscriber withdrawing from the connection and for recalling the attendant by flashing upon the main automatic exchange subscriber intermittently operating the switch hook.

In witness whereof, I hereunto subscribe my name this 30th day of December, A. D., 1924.

CLARENCE E. LOMAX.
